OF NEW YORK, N. Y., A CORPORATION OF NEW YORK.

REMOTE-CONTROL ELECTRICAL APPARATUS.

1,246,628.

Specification of Letters Patent. Patented Nov. 13, 1917.

Application filed July 9, 1913. Serial No. 778,158.

To all whom it may concern:

Be it known that I, CHALMERS P. WELLS, a citizen of the United States, and resident of the borough of Manhattan, city, county, and State of New York, have invented certain new and useful Improvements in Remote-Control Electrical Apparatus, of which the following is a specification.

This invention relates to electromagnetic apparatus for controlling electric circuits. The invention is shown in the drawing as arranged in a circuit to control a motor, and while the invention is particularly adapted for use in controlling the speed of a motor from a remote distance I desire it understood that I am not to be limited to that specific use of the invention.

The invention is shown as applied to an electric controller substantially like the apparatus shown in Patent No. 733,563, dated July 14, 1903 granted to A. Sundh.

When a solenoid core is at its lowest point the length of the air gap between the top of the core and the magnetic top bar or frame of the solenoid is at its maximum, therefore, this is the condition of greatest reluctance in the magnetic circuit. When the solenoid circuit is closed and the core begins to rise this air gap diminishes and the reduction of this gap increases the magnetic pull on the core. As the core continues to rise the air gap diminishes and the pull of the core is increased so that there is an accession of magnetic strength acting on the core as it rises.

In the embodiment of the invention shown in the drawings I have provided means progressively reducing the air gap between the solenoid core and its magnetic bracket or pole piece. I have also shown means for progressively reducing the magnetic pull on the core by automatically diminishing the pull of a portion of the lines of magnetic force drawing the core into the solenoid. I accomplish this by means of depending pins of magnetic material which are progressively engaged by the core as the said core moves upwardly or into the solenoid coil. It is to be understood that as each pin contacts with the top of the solenoid core the magnetic lines previously extending from the pin to the core and assisting in lifting the same are not strongly effective. A series of pins is arranged to be engaged in succession by the core as the core rises so that the pull-

ing lines of force are progressively and abruptly reduced in accordance with the number and area of pins engaged by the upper end of the core. It is manifest that as the pulling lines of force are reduced in effect, the upward pull on the core is diminished, the reduction in the magnetic lines substantially counterbalancing the increase in magnetic force due to the diminished air gap, so that the upward pull on the core remains substantially uniform throughout the upward movement thereof.

In the apparatus shown in the drawing the invention is applied to a controller designed to progressively change resistance in a motor circuit to thereby vary the speed of the motor. It is highly desirable in many instances that the motor speed be controlled from a remote point, and the controlling device must be so constructed that the remote control shall be positive, reliable and efficient. I secure these results by providing a resistance in the solenoid circuit and two circuit controlling switches or buttons, one of said switches being normally open to normally maintain the resistance in the solenoid circuit and the other button being normally closed to maintain the solenoid circuit closed. By means of this arrangement the movement of the solenoid core upward into its coil or downward from said coil may be positively controlled. When it is desired to increase the motor speed the solenoid circuit is completed around the resistance. As soon as the core contacts with the first pin of the series the resistance in series with the solenoid may be again cut into the circuit. The pulling strength of the solenoid will then not be sufficient to continue the upward movement of the core which would then tend to fall back, being retarded in its backward or downward movement by the dash pot shown. The core being sealed to the first pin of the series, however, there is sufficient magnetism produced by the coil with inserted resistance to support the core and to prevent further downward movement, the pin, of course, being supported on the upper bar of the solenoid. When it is desired to further increase the speed of the motor the resistance in the solenoid circuit is again short-circuited and the core will then move up to the next pin, the operation just described being then repeated. If it be desired to step down the speed of

the motor the solenoid circuit is broken by opening the normally closed push button and permitting the core to drop from one pin to the next longest pin in the series: 5 By then closing the circuit at the proper instant the core will be held. By this means the movement of the core into and out of its coil may be readily, accurately and continuously controlled, thereby varying the resistance in the motor circuit, either increasing or decreasing it, as may be desired.

In the drawing, Figure 1 is a vertical sectional view of the controller, a motor circuit and a series resistance being diagrammatically shown; and

15 Fig. 2 a plan view of the controller.

Fig. 3 a detail view of a modified form of the means for abruptly changing the number of effective lines of force influencing the 20 solenoid core; and

Fig. 4 a similar view of a slightly different form of device for the same purpose.

Referring to the various parts by numerals, 1 designates a solenoid provided with 25 a core 2 and the magnetic brackets or pole pieces 3 and 3^a. The lower end of the core is connected to a dash pot 4 of any desired construction. Pivoted to the solenoid pole piece 3 is a series of contact arms 5, 6, 7 and 30 8. Each of these arms is provided with a contact block 9 which is adapted to engage a complementary contact piece 10 carried by a rigid terminal bracket 11 above the solenoid. One end of the motor circuit is connected to this terminal bracket, the other end of said circuit being connected through 35 a resistance 12 with the contact arm 5. The contact arm 6 is also connected to the motor circuit in such manner that when it is brought into engagement with the terminal bracket 11 a portion of the resistance will be 40 cut out of the motor circuit. The contact arm 7 is similarly connected to the motor circuit so that upon its movement to its circuit closing position a still further portion 45 of the resistance will be cut out; and when the contact arm 8 has been moved to its circuit closing position, the motor circuit will be completed direct to the motor and all 50 of the resistance will be cut out. The resistance is in series with the motor armature so that as it is progressively reduced, the speed of the motor is progressively increased until it has reached its maximum.

55 The solenoid core carries a cam bracket 13 having cam engaging rollers or bars 14 which are adapted to engage cam surfaces 5^a, 6^a, 7^a and 8^a on the lower ends of the cam arms to force said arms to their circuit closing positions. These cams are arranged to 60 be engaged by the cam bracket at different points in the vertical movement of the core so that said arms will be brought to their closed position in succession as the core moves into the solenoid, as is fully pointed

out in the Sundh patent hereinbefore referred to.

Extending through the magnetic pole piece 3^a of the solenoid and into the path of the upper end of the solenoid core are three 70 loosely supported pins 15, 16 and 17 of magnetic material. These pins are of different lengths and extend different distances toward the core from the said pole piece. The pins are in direct contact with the pole piece 75 and are provided with heads or collars 15^a on their upper ends which in their normal positions rest on the pole piece. These collars may be made adjustable if desired. It is manifest that these pins alter the air gap 80 between the pole piece 3^a and the end of the core; and it is also obvious that the magnetic lines of force will extend between the said pins and the core. As the core rises and engages the ends of these pins the magnetic 85 lines exerting their influence upon the core are reduced abruptly and, consequently, the upward pull on the solenoid core is diminished. It is also obvious that this reduction in the magnetic lines is progressive as 90 the core rises, the maximum point of reduction being reached as the core contacts with the third pin.

To control the solenoid I provide the solenoid circuit 18 in which is arranged a closing push button 19; an opening switch or push button 20, and a resistance 21. The resistance 21 is sufficient to reduce the effective pull on the solenoid core so that when the switch 19 is open and the resistance 21 95 is in circuit with the solenoid there will be no effective pull on the solenoid core. The switch or push button 19 is normally open, while the switch 20 is normally closed. In order, therefore, to shunt the resistance 100 21 the switch 19 must be closed.

The operation of the device may be briefly described as follows:

Upon closing the solenoid circuit through the push button or switch 19, thereby shunting the resistance 21, the core immediately 110 moves upwardly and operates the first circuit closing arm 5, thereby closing the motor circuit through the resistance 12. This upward movement of the solenoid core 115 brings its upper end into contact with the pin 15, the longest of the three pins. The contact between this pin and the core eliminates the magnetic lines which had previously extended between said pin and the 120 solenoid core. Upon now opening the switch 19 and again throwing the resistance 21 into said circuit the effective pull of the coil on the core will be reduced and practically 125 eliminated and said core will settle down until the head of the pin 15 rests on the top of the solenoid pole piece 3^a. The core, however, will then be held in its raised position by the magnetic attraction between the end 130 of pin 15 and the end of the solenoid core.

- If it were not for the pin with its head engaging the top bar of the solenoid frame the core would continue its downward movement, but as the pin 15 and the core are sealed, that is to say in direct contact, there is enough magnetism produced by the coil when the resistance 21 is in circuit therewith to support the core and the attached dash pot.
- 10 The motor will then operate at its lowest speed. When it is desired to increase the motor speed the switch 19 is again closed, thereby causing the core to again move upwardly until it contacts with the pin 16 which is the next longest pin of the series. This further reduces the lines of force and diminishes the pull on the core. Upon again placing the resistance 21 in the solenoid circuit the solenoid core will be held in its upward position by means of the attraction between the pin 16 and the core, the head of this serving as means to hold the core against downward movement. This operation may be repeated when it is desired to still further increase the speed of the motor. It is clear, therefore, that I progressively reduce the lines of force or magnetic pull on the solenoid core as the air gap between the upper magnetic pole piece of the solenoid and the core is diminished.
- 15 To progressively increase the resistance in the motor circuit and thereby progressively decrease the speed of the motor the operation just described is substantially reversed. Assuming the core to be in contact with pin 17 and the motor to be operating at its highest speed, and it be desired to reduce the speed of the motor the switch 20 is opened thereby opening the solenoid circuit. The core will immediately drop, being, of course, retarded by the dash pot. When the core has left pin 17 and it be desired to hold it on pin 16, switch 20 would then be closed. By thus again completing the solenoid circuit through the resistance 21 the core would be held sealed to the pin 16 precisely as hereinbefore described. This operation would be again repeated when it is desired to drop the core to the end of the pin 15.
- 20 It is, of course, to be understood that the number of pins corresponds to the number of steps in the resistance so that the speed of the motor may be stepped up or down, as desired.
- 25 Successive abrupt changes in the number of effective lines of force influencing the solenoid core may be secured in various ways. In Fig. 3 is shown a series of spines 15', 16' and 17' of different lengths in proximity to the core 2^a and surrounding the same, said spines acting in a manner similar to the pins 15, 16 and 17 except that the spines need not contact directly with the core. The same result may also be obtained by concentric cylindrical tube of varying thicknesses as shown in 15", 16" and 17" in Fig. 4, said tube receiving the core 2^b and producing the abrupt changes in the number of effective lines, as herein described.
- 30 What I claim is:
1. A solenoid, a circuit therefor including a resistance, means for shunting said resistance to cause the core to move into the coil, said means being operative independently of the solenoid core, a series of loosely mounted headed magnetic pins of different lengths extending into the bore of the solenoid from one end thereof, the heads forming stops to limit the inward movement of said pins, the inner ends of said pins being in the path of the core and adapted to be progressively engaged by the core as it moves into the coil whereby the core will be magnetically held in position by the contact pins when the said resistance is in circuit with the solenoid coil. 70
2. A solenoid, a circuit therefor, a resistance in said circuit, means independent of the solenoid for shunting said resistance to cause the core to move into the coil, a series of loose, magnetic pins of different lengths extending into the bore of the solenoid with their axes parallel with the axis of the core, the inner ends of said pins being in the path of the core and adapted to be progressively engaged by the core as it moves into its coil, the magnetic influence of each one of said pins being sufficient to hold the core against outward movement when the resistance is in circuit with the solenoid coil after 80 the core has reached any one of said pins. 90
3. A solenoid, a core therefor, a series of headed magnetic pins of different lengths extending into the bore of the coil and adapted to be engaged in succession by the end of the core as it moves into the coil, the axes of said pins being parallel to the axis of the core, said pins as they contact with the core reducing the effective magnetic lines influencing the core to approximately offset the increase in magnetic pull due to the inward movement of the core and each of said pins having sufficient magnetism to sustain the core in the coil when the resistance is inserted in the solenoid circuit after the core 105 has contacted with one or more of said pins, and means independent of the solenoid for placing the resistance in the solenoid circuit to reduce the pull on the core. 110
4. A solenoid including a core, a circuit therefor, a resistance in said circuit sufficient to reduce the effective pull of the coil, manually operable means for shunting said resistance to cause the core to be moved into its coil, said means being also operable to 120 insert said resistance in said circuit, a series of loose, magnetic pins of different lengths extending into the bore of the solenoid with their axes parallel with the axis of the core, the inner ends of said pins being in the path 125 130

4
of the core as it moves into its coil, the magnetic influence of each one of said pins being sufficient to hold the core against outward movement when the resistance is in circuit with the solenoid coil after the core has reached any one of said pins, and manually operable means for opening the solenoid circuit to permit the core to move out of its coil, whereby the core may be controlled in

a step by step movement into and out of its coil.

In testimony whereof I hereunto affix my signature in the presence of two witnesses.

CHALMERS P. WELLS.
